No. 36,749.

Patented January 26, 1904.

UNITED STATES PATENT OFFICE.

JOHN B. WEIR AND IRA D. PERRY, OF CHICAGO, ILLINOIS.

DESIGN FOR A MONEY-BANK.

SPECIFICATION forming part of Design No. 36,749, dated January 26, 1904.

Application filed September 12, 1903. Serial No. 173,016. Term of patent 7 years.

To all whom it may concern:

Be it known that we, JOHN B. WEIR and IRA D. PERRY, citizens of the United States of America, and residents of Chicago, Cook county, Illinois, have invented a new, original, and ornamental Design for Money-Banks, of which the following is a specification.

In the accompanying drawings, Figure 1 is a side elevation of a bank, showing our new design. Fig. 2 is a front elevation of the bank shown in Fig. 1. Fig. 3 is a rear elevation of the bank shown in Figs. 1 and 2.

What we claim is—

The ornamental design for a money-bank, substantially as herein shown.

Signed by us at Chicago this 8th day of September, 1903.

JOHN B. WEIR.
IRA D. PERRY.
